UNITED STATES PATENT OFFICE.

CHARLES E. SIMPSON, OF CHICAGO, ILLINOIS.

FIRE-DOOR.

SPECIFICATION forming part of Letters Patent No. 727,854, dated May 12, 1903.

Application filed March 18, 1901. Serial No. 51,639. (No model.)

To all whom it may concern:

Be it known that I, CHARLES E. SIMPSON, a citizen of the United States, and a resident of Chicago, in the county of Cook and State of Illinois, have invented certain new and useful Improvements in Fire-Doors; and I do hereby declare that the following is a full, clear, and exact description thereof, reference being had to the accompanying drawings, and to the letters of reference marked thereon, which form a part of this specification.

This invention relates to improvements in fire-doors, and more particularly to a fire-door designed to be automatically self-closing at a temperature predetermined. Heretofore many types of fire-doors have been devised, some of which are designed to close automatically and many of which are expensive in construction and unsatisfactory in operation. The object of this invention is to provide cheap, simple, and effective means acting positively to close a door when a predetermined degree of temperature is reached.

The invention consists of the matters hereinafter described, and more fully pointed out and defined in the appended claims.

In the drawings, Figure 1 is a front elevation of a wall provided with a door embodying my invention, showing the same in its open position. Fig. 2 is a similar view showing the door closed.

In said drawings, A indicates a wall (as shown of brick or tile, though obviously the same may be of any desired material) provided with a door-aperture therethrough.

B B' indicate two half-doors oppositely movable and of such a size that when brought together they entirely close the door-aperture. Said half-doors are slidably secured in ways C, herein shown as metallic and rigidly bolted to the wall in a vertical position and each having permanently secured thereon a sheave c, through which passes a chain or other flexible connection c'. The upper end of said chain is secured near the bottom of the half-door B, and the other end extends downwardly along the ways and is secured to a rod c², rigidly secured on the lower half-door B' and extending upwardly therefrom.

As shown, said lower half-door is provided at its top with a transverse flange of metal projecting laterally from the door transversely

of said ways, and said rods c² pass through the ends of said flange and are rigidly secured thereto by means of a nut or the like. Said half-doors are approximately of the same weight and when opened normally remain in said position, each serving to counterbalance the other. The length of said chains and rods is such that said half-doors meet centrally when in their closed position, with the upper end of said rods terminating at the sheaves. For the purpose of automatically actuating said doors to close the same a sheave D is secured upon the wall centrally above the door and a weight D' supported thereon by means of a chain d, one end of which is permanently secured to the wall and contains a fusible or thermostatic link of any desired kind. At each side of and above the door and below said sheave D is rigidly secured a trip mechanism E, which is provided with an inwardly-swinging latch e and a levered hook e', adapted to be normally held in a supporting position by means of said latch, as shown in Fig. 1. A chain or other flexible connection connects said latches e, and said weight D' is connected thereto by means of a chain e², which is normally slack.

G indicates rods or arms projecting laterally beyond the ways and rigidly secured to the half-door B, near the top thereof, and vertically apertured near the ends thereof. A rod g extends downwardly through each of said arms and is straight for the greater part of its length, and the ends of each rod are bent parallel with each other and apertured to receive the rod g', which extends therethrough. A relatively short chain provided with an enlarged link at its upper end for engagement with the hook e' of the trip mechanism is secured on the upper end of each rod g'. Weights are rigidly secured on each rod g', one of which on each rod, as shown, is an enlargement or ball g², located intermediate of the ends of the rod and in position to support the rods g g from arms G when the doors are in their open position, as shown in Fig. 1. A weight G' is rigidly secured on each of the rods g g at the upper end thereof, which project laterally a sufficient distance to carry said weight away from the rod g' g'. A weight G² is secured on the lower end of each rod g'.

The operation of my device is as follows: The door may be opened or closed ordinarily as other doors, without recourse to the emergency mechanism, the rods $g\ g$ being of such length as not to interfere with the ordinary movements of the half-doors in closing. The length of the chain c' limits the distance that the half-door B may descend and the half-door B' ascend. Should the temperature in the air above the doors rise to the danger-point, and obviously the temperature will always be highest in the top of a room, the fusible link d' parts, permitting the weight D to drop, thereby jerking the latches $e\ e$ inwardly by means of the chains e^2 and releasing the trip-levers. The chains are thereby released from the hooks thereof, and the rods $g'\ g'$ fall. When the support of said rod g' is removed from the rods $g\ g$ and weights $G'\ G'$, they fall and engage the bracket-arms $G\ G$, so that the entire gravity of the weights $G'\ G'$ and rods $g\ g$ is added to the normal weight of the half-door B, thereby causing the same greatly to overbalance the weight of the half-door B' and to descend and pull up the half-door B'. Should the half-doors not close under the impulse given by the gravity of the weights $G'\ G'$ and rods $g\ g$, the enlargements on the rods $g'\ g'$ as said rods fall at last engage the ends of the rods $g\ g$, thereby giving an additional closing impulse to the half-doors. It will thus be seen that a plurality of closing impulses may be given to the half-doors, insuring that the doors will be effectively closed.

Obviously a device of the class described may be used to close any opening in a wall. It is not imperative, however, that the apparatus be embodied with a vertically-movable door, inasmuch as a similarly-operating device can be made to close laterally-movable doors.

Many details of construction may be varied without departing from the principle of this invention.

I claim as my invention—

1. The combination with parallel ways, of oppositely-movable half-doors slidably secured in said ways, means whereby movement in one of said doors produces opposite movement in the other, and means whereby weights normally unsupported on the doors act in a plurality of impacts to close said doors at a given temperature.

55 2. In a device of the class described, the combination with parallel ways, of half-doors oppositely movable therein, means for limiting such movement, weights slidably connected with the door, means for normally supporting the weight free from the door and means for releasing said weights onto the door in a plurality of impacts at a predetermined temperature thereby closing the door.

65 3. In a device of the class described, parallel ways, oppositely-movable mutually-counterbalancing half-doors slidably secured in said ways, means for limiting the movement

of said doors, distinct weights normally supported free from said half-doors at different heights, means for releasing said weights to strike in succession upon one of said doors at a predetermined point in temperature.

4. In a device of the class described, parallel ways, oppositely-movable mutually-counterbalancing half-doors secured therein, a sheave rotatably secured on said ways, a flexible connection secured on each of said doors passing through said sheave, apertured arms on one of said doors, a rod secured therein extending parallel with said ways, a weight on said rod, a trip mechanism located adjacent to said doors and supporting the rod and weight free from said arms and means for releasing said trip mechanism therefrom at a predetermined temperature, thereby permitting the rod and weight to fall upon said arms and to actuate said half-doors to close.

5. The combination with parallel vertical ways, of an upper and a lower half-door oppositely movable therein, flexible connections between said half-doors, a sheave secured on each way over which sheaves said connections pass, apertured arms on the upper door, a rod having a weight thereon slidably secured therein and extending downwardly along each way, said rod being bent outwardly and apertured at its ends, a weighted supporting-rod secured in said apertures, means thereon engaging and supporting the first-named rod, a trip mechanism located above and on each side of the door and on which said supporting-rods are secured and means for automatically releasing the trip mechanism at a predetermined temperature.

6. In a device of the class described, vertical ways, oppositely-movable counterbalancing half-doors secured therein, flexible connections between said doors, sheaves on said ways over which said flexible connections extend, apertured bracket-arms on the upper door, a guide-rod passing through said apertures having its ends bent outwardly and apertured, a weight secured on said guide-rod, a supporting-rod normally supported on trip mechanism at the side of the doors, an enlargement thereon on which said guide-rod and the weight thereof are supported, flexible connections between said trip mechanism and a weight attached thereto and fusible means forming the connection.

7. In a device of the class described, oppositely-movable half-doors, a plurality of slidably-connected weights supported free from and above the doors on each side thereof, trip mechanisms located above and on each side of said doors, and flexible connections between the same, a weight suspended by a chain having a fusible link, and loosely connected to the flexible connections, said weight when released acting automatically to release the slidably-connected weights on each side of the door, whereby a plurality of impulses is exerted to close the doors.

8. In a device of the class described, a door,

a rod apertured at its ends slidably secured thereon, a weight attached thereto, a weight-
ed rod passing through said apertured ends and slidably secured to the apertured rod and
5 normally engaging and supporting the same with its weight free from the door.

9. In a device of the class described, the combination with parallel ways, of slideable doors therein, a plurality of slideably-connected weights supported free from and above the doors on each side thereof, and slideably connected therewith, trip mechanism located above and on each side of said doors and connected with said weights, a flexible connection between said trip mechanisms, a weight loosely connected with said flexible connection and normally supported free therefrom by fusible means.

10. In a device of the class described, the combination with parallel ways, of doors slid-

able therein, a weight suspended centrally above said doors by a chain having a fusible link, trip mechanism located above and on either side of said doors, a flexible means connecting said trip mechanisms, means acting 25 normally to connect said weight loosely with said flexible connection, a plurality of slideably-connected weights normally supported from said trip mechanisms, a plurality of apertured arms rigidly connected with one of 30 said doors and slideably connected with said weights adapted to receive an impact therefrom at a predetermined temperature.

In testimony whereof I have hereunto subscribed my name in the presence of two sub- 35 scribing witnesses.

CHARLES E. SIMPSON.

In presence of—

CHARLES W. HILLS,
ANNA B. HILLS.
